UNITED STATES PATENT OFFICE.

PAUL A. WARD, OF LOS ANGELES, CALIFORNIA.

SOLE AND STITCH REMOVING MACHINE.

Application filed August 6, 1923. Serial No. 655,990.

To all whom it may concern:

Be it known that I, PAUL A. WARD, a citizen of the United States, residing at Los Angeles, in the county of Los Angeles and State of California, have invented certain new and useful Improvements in Sole and Stitch Removing Machines, of which the following is a specification.

This invention relates to a sole and stitch removing machine, designed primarily for use in connection with shoe repairing work, although it is to be understood that the machine can be employed for any purposes wherein it is found applicable, and the invention has for its object to provide, in a manner as hereinafter set forth, a machine including a sole removing element and an old stitch removing element, operating synchronously for simultaneously disconnecting a sole from a welt and for removing the old stitches also from the welt.

A further object of the invention is to provide a machine, in a manner as hereinafter set forth and for the purpose referred to, including a cutter or knife element for severing a sole from a welt and further including a thread remover operating synchronously with the knife or cutter element for removing the old stitching from the welt as the sole is being severed therefrom, whereby a worn sole and its attached threads can be quickly removed from a welt to expedite the operation of the repairing of the shoe.

Further objects of the invention are to provide a machine, in a manner as herein-after referred to and for the purpose set forth, which is simple in its construction and arrangement, strong, durable, compact, thoroughly efficient and convenient in its use, readily assembled and comparatively inexpensive to set up.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:

Figure 1 is an elevation of a sole and

stitch removing machine, in accordance with this invention.

Figure 2 is a top plan, broken away, of the head of the machine illustrating the sole removing element as well as the thread removing element.

Figure 3 is an end view of the head illustrating the sole and thread removing elements.

Figure 4 is a longitudinal sectional view, broken away, of the head of the machine.

Referring to the drawings in detail, 1 denotes a standard of any suitable type and which is provided at its upper end with a pair of bearings 2, 3. Projecting laterally from the standard 1 below the top thereof, is a support 4, for an electric motor 5, which is connected in any suitable manner with a source of electrical energy. The motor shaft is indicated at 6 and is provided with a grooved pulley 7, for driving a transmission belt 8, which is trained over a grooved pulley 9, carried on the inner end of the operating shaft 10 of the machine. The shaft 10 is mounted in the bearings 2, 3, and projects from each end thereof, and the outer end of said shaft 10 is provided with an annular head 11 of materially greater diameter than the diameter of the shaft.

The standard 1 is formed with a lateral arm 12, having its outer end enlarged, as at 13, and which is disposed in parallelism with respect to the shaft 10, and secured to the enlarged end 13 is the flanged end 14 of a guard member 15, provided with an opening 16, for the passage of the head 11 of the shaft 10. The end terminal portion 17 of the member 15, is offset with respect to the remaining portion of said member 15, whereby the portion 17 will be offset in a direction towards the bearing 3. The offset terminal portion 17 has a part of one side edge thereof, as indicated at 18, disposed at an inward inclination, and the other side edge has a part thereof, as indicated at 19, extending at an inward inclination, but the inclination is less than the inclination of the part 18, whereby the end edge 20 of the member 15 will be disposed eccentrically with respect to the lengthwise center of said member 15. The inclined parts 18 and 19 of the side edges of the member 15 provide a tapered free terminal for the member 15 and which is eccentrically disposed, and furthermore which gradually reduces in thickness to

110

wards the end of said tapered terminal to provide what may be termed a sharp tapered terminal portion so that the latter can enter between the welt and the sole when the sole is being severed from the welt and which furthermore will protect injury to the welt during the operation of the knife or cutter element to be presently referred to.

Fixedly secured, by the hold-fast device 10, 21, to the shaft 10, is a collar 22, which is arranged in close proximity to the bearing 3 and rotates with the shaft 10. Extending laterally from the shaft 10 through the collar 22, as well as projecting from the latter, 15 is a pin 23, which has its outer end positioned within a lengthwise slot 24, formed in the inner end of a cup-shaped cylindrical carrier 25. The carrier 25 surrounds the collar 22 and has one end formed with an opening 26 for the passage of the shaft 10. Surrounding the shaft 10 and interposed between the collar 22 and that end of the carrier 25 which is provided with the opening 26, is an expanding element 27 which is illustrated by way of example, as a body of rubber, but if desired the said element 27 may be constructed of a coiled spring. The function of the element 27 is to normally shift the carrier 25 in a direction towards 20 the head 11 of the shaft 10. The carrier 25 is provided with an opening 28, to permit of access being had to the holdfast device 21.

Secured to one end of the carrier 25, by the hold-fast devices 29, is the stitch removing element and which is interposed between the carrier 25 and the head 11, and is further maintained in permanent contact with the head 11 through the medium of the expanding element 27. The stitch removing 35 element consists of a disk 30 provided with a series of tangentially disposed oval-shaped slots 31, having formed integral with one edge thereof a semi-oval shaped rib 32 which acts against the welt to remove the stitching 40 therefrom after the cutter element to be presently referred to has severed the stitching between the sole and the welt. The stitch removing element operates against that face of the welt opposite that face 45 which is secured to the sole and from which the sole is disconnected.

The pin 23 provides for the bodily rotating of the carrier 25 with the shaft 10, and as the stitch removing element is fixedly 50 secured to one end of the carrier 25, it is obvious that said element rotates with the shaft and carrier. The stitch removing element is spaced a substantial distance from the guard member.

60 The knife or cutter element consists of an oscillatory bar 33, pivotally connected as at 34 to the enlarged outer end 13 of the arm 12. The bar 33 is provided near its free end with an oval-shaped slot 35 through which 65 extends a headed pin 36, which is secured

to the head 11 of the shaft 10. The pin 36 is eccentrically disposed with respect to the axis of the head 11. Adjustably connected to the free end of the bar 33, is a cutter member or knife 37, having an angularly disposed cutting terminal 38 which operates between the welt and the sole for the purpose of severing the stitching whereby the sole is disconnected from the welt and the welt during the severing of the stitching by 75 the cutting terminal is protected through the medium of the guard member 15.

The shoe is positioned with respect to the cutter element and stitch removing element in such manner that the stitch removing element 80 will operate against that face of the welt opposite the face to which the sole is attached for the purpose of removing the old stitching when the cutter element severs the stitching to disconnect the sole. The ribs 85 32 acting against the loose stitching will quickly remove the same from the welt immediately upon the severing of the stitching by the knife. When the shoe is positioned with respect to the machine, for the purpose 90 of removing the sole, the cutting terminal 38 is arranged to extend between the sole and the welt for the purpose of severing the stitching, and owing to the oscillation of the bar 33, the said cutting terminal 38 will 95 act to sever the stitching thereby disconnecting the sole from the welt.

The stitch removing element synchronously rotates during the oscillatory movement of the cutter element, due to the fact that 100 both elements are driven from the shaft 10 simultaneously.

Although the preferred embodiment of the invention is as described and shown, yet it is to be understood that changes in the 105 details of construction can be had which will fall within the light of the invention as claimed.

What I claim is:—

1. A machine for the purpose set forth 110 comprising a cutter element for severing the stitching between a welt and a sole, a stitch removing element operating against the welt for removing the severed stitching, and means for synchronously operating said elements.

2. A machine for the purpose set forth 115 comprising a cutter element for severing the stitching between a welt and a sole, a stitch removing element operating against the welt for removing the severed stitching, means for synchronously operating said elements, and a guard member arranged in operative relation with respect to said cutter element to protect the welt during the severing of 120 the stitching by said cutter element.

3. A machine for the purpose set forth 125 comprising an oscillatory cutter element for severing the stitching between a welt and a sole, a rotatable thread removing element 130

- operating against that face of the welt opposite that face to which is secured the sole for removing the severed stitching, and a common driving means for said elements for 5 simultaneously operating them.

4. A machine for the purpose set forth comprising an oscillatory cutter element for severing the stitching between a welt and a sole, a rotatable thread removing element operating against that face of the welt opposite that face to which is secured the sole for removing the severed stitching, a common driving means for said elements for 10 simultaneously operating them, and a guard member arranged in operative relation with respect to said cutter element for protecting the welt during the severing of the stitching by said cutter element.

5. A machine for the purpose set forth 15 comprising a cutter element for severing the stitching between a welt and a sole, a stitch removing element operating against the welt for removing the severed stitching, and means for synchronously operating said elements, said stitch removing element including a series of tangentially disposed slots having projecting from one edge thereof a semi-oval shaped rib.

6. A machine for the purpose set forth 20 comprising a cutter element for severing the stitching between a welt and a sole, a stitch removing element operating against the welt for removing the severed stitching, means for synchronously operating said elements, 25 and a guard member arranged in operative relation with respect to said cutter element to protect the welt during the severing of the stitching by said cutter element, and a resilient element acting to maintain said thread removing element acting against the welt.

7. A machine for the purpose set forth 30 comprising an oscillatory cutter element for severing the stitching between a welt and a sole, a rotatable thread removing element operating against that face of the welt opposite that face to which is secured the sole for removing the severed stitching, a common driving means for said elements for 35 simultaneously operating them, and a resilient element acting to maintain said thread removing element against the welt.

8. A machine for the purpose set forth 40 comprising an oscillatory cutter element for severing the stitching between a welt and a sole, a rotatable thread removing element operating against that face of the welt opposite that face to which is secured the sole for removing the severed stitching, and a common driving means for said elements for 45 simultaneously operating them, said stitch removing element including a series of tangentially disposed slots having projecting from one edge thereof a semi-oval shaped rib.

9. A machine for the purpose set forth 50 comprising a cutter element for severing the stitching between a welt and a sole, a stitch removing element operating against the welt for removing the severed stitching, means for synchronously operating said elements, and said cutter element including an adjustable cutter member provided with an angularly disposed cutting terminal.

10. A machine for the purpose set forth 55 comprising a cutter element for severing the stitching between a welt and a sole, a stitch removing element operating against the welt for removing the severed stitching, means for synchronously operating said elements, 60 and a resilient element acting to maintain said thread removing element against the welt.

11. A machine for the purpose set forth 65 comprising an oscillatory cutter element for severing the stitching between a welt and a sole, a rotatable thread removing element operating against that face of the welt opposite that face to which is secured the sole for removing the severed stitching, a common driving means for said elements for 70 simultaneously operating them, and a resilient element acting to maintain said thread removing element against the welt.

12. A machine for the purpose set forth 75 comprising an oscillatory cutter element for severing the stitching between a welt and a sole, a rotatable thread removing element operating against that face of the welt opposite that face to which is secured the sole for removing the severed stitching, a common driving means for said elements for 80 simultaneously operating them, a guard member arranged in operative relation with respect to said cutter element for protecting the welt during the severing of the stitching by said cutter element, and a resilient element acting to maintain said thread removing element against the welt.

13. A machine for the purpose set forth 85 comprising a cutter element for severing the stitching between a welt and a sole, a stitch removing element operating against the welt for removing the severed stitching, means for synchronously operating said elements, and said cutter element including an adjustable cutter member provided with an angularly disposed cutting terminal.

14. A machine for the purpose set forth 90 comprising a cutter element for severing the stitching between a welt and a sole, a stitch removing element operating against the welt for removing the severed stitching, means for synchronously operating said elements, 95 and a resilient element acting to maintain said thread removing element against the welt.

15. A machine for the purpose set forth 100 comprising an oscillatory cutter element for severing the stitching between a welt and a sole, a rotatable thread removing element operating against that face of the welt opposite that face to which is secured the sole for removing the severed stitching, a common driving means for said elements for 105 simultaneously operating them, a guard member arranged in operative relation with respect to said cutter element for protecting the welt during the severing of the stitching by said cutter element, and a resilient element acting to maintain said thread removing element against the welt.

16. A machine for the purpose set forth 110 comprising an oscillatory cutter element for severing the stitching between a welt and a sole, a rotatable thread removing element operating against that face of the welt opposite that face to which is secured the sole for removing the severed stitching, a common driving means for said elements for 115 simultaneously operating them, a guard member arranged in operative relation with respect to said cutter element for protecting the welt during the severing of the stitching by said cutter element, and a resilient element acting to maintain said thread removing element against the welt.

17. A machine for the purpose set forth 120 comprising an oscillatory cutter element for severing the stitching between a welt and a sole, a stitch removing element operating against the welt for removing the severed stitching, means for synchronously operating said elements, and said cutter element including an adjustable cutter member provided with an angularly disposed cutting terminal.

18. A machine for the purpose set forth 125 comprising an oscillatory cutter element for severing the stitching between a welt and a sole, a stitch removing element operating against the welt for removing the severed stitching, means for synchronously operating said elements, and a resilient element acting to maintain said thread removing element against the welt.

for synchronously operating said elements, a guard member arranged in operative relation with respect to said cutter element to protect the welt during the severing of the stitching by said cutter elements, and said cutter element including an adjustable cutter member provided with an angularly disposed cutting terminal.

15. A machine for the purpose set forth comprising an oscillatory cutter element for severing the stitching between a welt and a sole, a rotatable thread removing element operating against that face of the welt opposite that face to which is secured the sole for removing the severed stitching, a common driving means for said elements for simultaneously operating them, and said cutter element including an adjustable cutter member provided with an angularly disposed cutting terminal.

16. A machine for the purpose set forth comprising an oscillatory cutter element for severing the stitching between a welt and a sole, a rotatable thread removing element operating against that face of the welt opposite that face to which is secured the sole for removing the severed stitching, a common driving means for said elements for simultaneously operating them, a guard member arranged in operative relation with respect to said cutter element for protecting the welt during the severing of the stitching by said cutter element, and said cutter element including an adjustable cutter member provided with an angularly disposed cutting terminal.

In testimony whereof, I affix my signature hereto.

PAUL A. WARD.
